Primary Examiner—James R. Largen**Attorney, Agent, or Firm—Terry M. Gernstein****[57]****CLAIM**

The ornamental design for a bathtub insert seat for a child, as shown and described.

DESCRIPTION

FIG. 1 is a perspective view taken from the top, rear and left end of a bathtub insert seat for a child showing my new design;

FIG. 2 is a front elevational view thereof;

FIG. 3 is a rear elevational view thereof;

FIG. 4 is a right end elevational view thereof;

FIG. 5 is a left end elevational view thereof; and,

FIG. 6 is a top plan view thereof.

It is to be understood that the bottom of the insert is plain and unornamented.

FIG. 1.

FIG. 4.

FIG. 2

FIG. 5.

FIG. 3.

FIG. 6.
